SAFETY RAZOR

George Taylor, Pentwortham, Preston, England

Application August 19, 1932, Serial No. 629,523
In Great Britain September 22, 1931

7 Claims. (Cl. 30—12)

This invention relates to safety razors having a blade carrier mounted for reciprocation by means of a face roller which is rotated during shaving.

Heretofore, it has been proposed to operate the blade carrier by means of a serrated face roller at the front of the razor frame, with a cam groove actuating a pin on the carrier, which has been mounted on two longitudinal rods set at the required site angle.

The chief object of the present invention is to simplify the means by which the blade carrier is mounted on the razor frame and operated by the face roller.

To this end according to the invention, the blade carrier is tiltably mounted in the frame by a single guide support at the rear of the frame, and means on the frame is provided for engaging with and over the blade to determine the set of the operative edge of the blade in relation to the face roller.

Reciprocation of the carrier is preferably effected by a pin on the carrier engaging in a cam groove in the face roller and limit means is provided for holding the pin in the cam groove when the blade is removed from the carrier.

Conveniently, a backing plate is employed for fastening the blade on the carrier with one edge adjacent the face roller. The backing plate may be hinged to the carrier or so disposed that it forms a guide plate which is hinged to some portion of the frame of the razor and covers the razor blade when in operative position.

In the case where the backing plate is hinged to the carrier the razor blade may be attached to the latter by means of a catch, which when the plate is closed, projects through a hole in the razor blade to the underside of the carrier and is held by means of a clasp mounted on the carrier, which clasp is preferably pivoted to the carrier.

Preferably, the means for determining the set of the blade in relation to the face roller is constituted by blade guides one at each side of the frame adjoining the face roller, the blade entering the recesses formed in these guides, so that upon reciprocation it is constrained to move always in the same position as set by the guides.

Alternatively, in the case where the backing plate is hinged to the frame, projections may be formed at the forward edge of the backing plate, which, when the plate is in its operative position, locates it with regard to the face roller and the blade and determines the set of the latter in relation to the face roller. In this form the back-

ing plate is spring-controlled so as to hold the blade in position on the carrier, which is provided with steady projections which are adapted to cooperate with recesses in the blade. In order to limit the tilting movement of the carrier on its single guide member, that is to say, movement which would cause the carrier to come out of engagement with the cam action associated with the face roller, abutments may be provided on the frame of the razor by which movement in one or other direction is limited, or, alternatively, the guide bar may be of rectangular section, the carrier being provided with corresponding eyelets by which the carrier is mounted on the guide bar, and which prevent excessive tilting movement.

The invention will be more clearly understood with reference to the accompanying drawing, which shows three forms of the invention.

In the drawing—

Fig. 1 is a full size side elevation of one form with the backing plate holding the blade in position;

Fig. 2 is a plan of Fig. 1 with the backing plate lifted about its hinge;

Fig. 3 is a side section elevation on the line III—III of the Fig. 2 drawn to double size;

Fig. 4 shows another form of razor according to the invention, the view being a section shown similar to that of Fig. 3, while

Fig. 5 is a further form of the invention, the view being a section shown similar to that of Fig. 3.

Like reference numerals in the drawing designate like or similar parts.

The razor comprises a handle 1, screwed to a bridge piece 2, secured to a holder frame 3 including side plates 3a carrying between them at one end a serrated face roller 8, having a cam groove 9 in which a pin 10 on the tilttable carrier 11 operates, the groove being such as to cause the carrier to reciprocate when the roller is rotated.

In Figs. 1 to 3, the single guide bar for pivotally mounting the carrier 11 comprises a longitudinal rod 12 of circular cross section, mounted at the rear end of the side plates of the frame 3 relatively above the face roller, the carrier being tiltably and slidably carried on the rod 12 by means of eyelets 13.

In order to limit the tilting movement of the carrier so as to prevent the pin 10 coming out of engagement with the cam groove 9—this tilting movement being a rocking movement—lugs 14 are provided on the frame 3 near the guide bar 12 to limit movement of the carrier in an upward direction, and abutments or stop pins 15 are located

cated on the frame 3 beneath the carrier to form a support therefor, limiting its downward movement, these pins conveniently being formed by the screws which secure the bridge piece 2 to the frame 3.

The blade 16 is provided with recesses which co-operate with steady pins 17 on the carrier 11, and the blade is secured to the carrier by means of a backing plate 18, hingedly connected at 19 to the carrier and provided with a catch 20, adapted to pass through a slot 21 in the blade 16 and co-operate with a clasp 22 pivoted at 23 to the underside of the carrier. The set of the blade 16 with respect to the roller 8 is determined during reciprocation by means of blade guides 24, one at each side of the frame 3, and constituted by turned over lugs forming recesses 25, in which the blade 16 reciprocates.

It will be clear that to some extent the stops 15 will assist in determining the set of the blade, although this will be mainly accomplished by the recesses 25.

In a modified form of razor as shown in Fig. 4, the single guide bar for the carrier is constituted by a rod 26 of rectangular cross section, with which tiltably engage slots in straight eyelets 27, fixed to the carrier 11. This rod 26 limits the rocking movement of the carrier, which in this case, slides upon the upper surfaces of the sides 30 of the frame 3, and within the guides 24.

In the two previously described constructions, the backing plate 18 is hinged to the carrier 11, but in the construction according to Fig. 5 the backing plate is formed as a spring-controlled member hinged to the frame 3, the sides of which are constituted by L-shaped members 28, between which the face roller 8 is mounted and which are connected by the bridge piece 2. The carrier 11 is mounted to reciprocate by means of a single rear supporting rod, constituted by projections 29 of rectangular cross section, extending from the ends of the carrier into slots formed in the up-standing portions of the L-shaped sides 28, the slots constituting the pivot support for the carrier 40 in which the projections can tilt slightly, but the carrier may reciprocate without any appreciable rock, by the means now to be described.

In order to provide an underneath support for the carrier, supplementary supporting or limit 50 stops 30 may be provided which are screwed into the bridge piece 2 so as to provide for adjustment of the set of the blade—when this is mounted on the carrier—with respect to the face roller. The backing plate is constituted by a bent over plate 55 31, having its bent over edge hingedly connected at 32 between the sides 28, and spring-controlled by means of a lug 33 fixed to the plate 31, and co-operating with a spring 34 secured to the bridge piece 2 and pressing upon the lug 33.

This plate 31 forms a guide for the razor blade, and when in its operative position as shown in Fig. 5, determines the set of the blade in relation to the face roller, by means of projections 35, one at each end of its forward edge, which 60 bear on the sides 28 clear of the ends of the blade, but with the forward edge of the plate 31 adjacent the blade so as to ensure that it cannot rise from its position. The blade 16 is located upon the carrier by means of steady pins 17 and also held by means of a groove 36 formed by turning over the rear edge of the carrier as shown.

It will be seen that the blade is prevented from dropping because of the rectangular shape of the rear supporting projections 29, and also by means

of the stop pins 30 on the frame. Consequently, in conjunction with the backing plate 31, a very accurate set of the blade is ensured. If desired, in this construction the blade may be further secured by means of pivoted catches secured to the sides of the carrier.

By use of this invention, an easily reciprocating movement is given to the blade, which enhances its capacity to shave cleanly, and further, the construction is simple and easy to make, and the setting of the blade is effected independently of the carrier support so that accuracy of the setting obtains over long periods with a consequent improvement in the useful life of the razor.

What I claim is:—

1. In a safety razor including a holder frame, a face roller mounted at the front of the frame, and a reciprocating blade carrier operable by the face roller, the combination with the holder frame of a carrier support mounted on a single guide carrier at the rear of the said frame with a limited amount of play, a blade on the carrier, end plates to the holder having guide surfaces thereon for the front corners of the blade and guard lugs thereon to prevent lifting of the blade, a tongue on the carrier engaging the slot in the face roller, and means for fixing the blade on the said carrier so that the setting is governed by the surfaces of the end plates, while the play allowed in the rear guide does not affect the setting, but prevents disengagement of the tongue from its slot when the blade is removed.

2. In a safety razor including a holder frame, a face roller mounted at the front of the frame, and a reciprocating blade carrier operable by the face roller, the combination with the holder frame of a carrier support mounted on a rod extending across the rear of the said frame with a limited amount of play, a blade on the carrier, end plates to the holder having guide surfaces thereon for the front corners of the blade, and guide lugs thereon to prevent lifting of the blade, a tongue on the carrier engaging the slot in the face roller, and means for fixing the blade of the said carrier so that the setting is governed by the surfaces of the end plates while the play allowed in the rear guide does not affect the setting, but prevents disengagement of the tongue from its slot when the blade is removed.

3. In a safety razor including a holder frame, a face roller mounted at the front of the frame, and a reciprocating blade carrier operable by the face roller, the combination with the holder frame of a carrier support mounted on a single guide carrier at the rear of the said frame with a limited amount of play, abutments on the said frame above and below the carrier limiting the rocking movement of the latter, a blade on the carrier, end plates to the holder having guide surfaces thereon for the front corners of the blade, and guard lugs thereon to prevent lifting of the blade, a tongue on the carrier engaging the slot in the face roller, and means for fixing the blade of the said carrier so that the setting is governed by the surfaces of the end plates while the play allowed in the rear guide does not affect the setting, but prevents the disengagement of the tongue from its slot when the blade is removed.

4. In a safety razor including a holder frame, a face roller mounted at the front of the frame, and a reciprocating blade operable by the face roller, the combination with the holder frame of a carrier support mounted on a single guide car-

- rier at the rear of the said frame with a limited amount of play, a blade on the carrier, end plates to the holder having guide surfaces thereon for the front corners of the blade and guard lugs thereon to prevent lifting of the blade, a tongue on the carrier engaging the slot in the face roller, a hinged cover fixing the blade on the said carrier through perforations in the blade, and means for fastening the cover to the carrier on the underneath side thereof. 5
5. In a safety razor including a holder frame, a face roller mounted at the front of the frame, and a reciprocating blade operable by the face roller, the combination with the holder frame of a carrier support mounted on a single guide carrier at the rear of the said frame with a limited amount of play, a blade on the carrier, end plates to the holder having guide surfaces thereon for the front corners of the blade, and guard lugs thereon to prevent lifting of the blade, a tongue on the carrier engaging in the face roller, a hinged cover fixing the blade on the said carrier through perforations in the blade, and a pivot catch engaging a clasp passing through the blade and the carrier so as to fix the cover and the blade thereon by angular movement about its pivot. 10
6. In a safety razor including a holder frame, a face roller mounted at the front of the frame, and a reciprocating blade operable by the face roller, the combination with the holder frame of a carrier support mounted on a single guide carrier at the rear of the said frame with a limited amount of play, a blade on the carrier, end plates to the holder having guide surfaces thereon for the front corners of the blade, and guard lugs thereon to prevent lifting thereof, a tongue on the carrier engaging in the face roller, means for fixing the blade on the said carrier so that the setting is governed by the surfaces of the end plates, and a bridge piece connecting the end frames of the holder about centrally between the face roller and the carrier guide, and a handle thereon centrally of the holder. 15
7. In a safety razor including a holder frame, a face roller mounted at the front of the frame, and a reciprocating blade carrier operable by the face roller, the combination with the holder frame of a carrier support having a rectangular bar at the rear of the said frame, a blade on the carrier, end plates to the holder having guide surfaces thereon for the front corners of the blade, and guard lugs thereon to prevent lifting of the blade, a tongue on the carrier engaging in the face roller, and means for fixing the blade on the said carrier so that the setting is governed by the surfaces of the end plates, while the play allowed in the rear guide does not affect the setting, but prevents disengagement of the tongue from its slot when the blade is removed. 20
